HIS ATTORNEY

UNITED STATES PATENT OFFICE

WALTER C. HOFFMAN, OF MAYWOOD, ILLINOIS

DISPLAY HOLDER FOR CARDS

Application filed April 26, 1929. Serial No. 358,327.

This invention relates to certain novel improvements in display devices and more specifically to display devices for greeting cards and the like and has for its principal object the provision of an improved construction of this character which will expedite the displaying of the cards and the envelopes therefor in a manner which will prevent soiling of the displayed cards.

Another object of the invention is to provide a container in combination with the display device in which a supply of cards may be contained.

Another object of the invention is to arrange a device of the foregoing character in a manner such that cards may be expeditiously inserted into the device.

A still further object of the invention is to provide a device of the above named character in a manner such that indicating means will be associated with the various members of the display device in order that selected cards may be expeditiously marked.

Other objects will appear hereinafter.

The invention consists in the novel combination and arrangement of parts to be hereinafter described and claimed.

The invention will be best understood by reference to the accompanying drawings, showing the preferred form of construction and in which:

Fig. 1 is a front elevational view of a preferred form of construction for my display device in association with a cabinet or housing therefor;

Fig. 2 is a vertical sectional view taken substantially on the line 2-2 on Fig. 1;

Fig. 3 is a fragmental view depicting one of the card holding members in my improved display device;

Fig. 4 is a view substantially similar to Fig. 3 depicting one of my improved display devices in partially opened position, said view depicting what I term a two card holder and showing cards disposed therein; and

Fig. 5 is a view substantially similar to Fig. 4 depicting a three card holder in fully open position.

In the accompanying drawings wherein I have illustrated a preferred form of con-

struction for my device 10 and 11 indicate the end members for my improved display device which are preferably arranged so as to be substantially triangular in formation with the apices thereof arranged at substantially the midpoint in their extent. The end members 10 and 11 extend upwardly from a back plate 12.

The display device is preferably arranged on a container generically indicated by 13 which includes a compartment 14 in which shelves 15 are provided and access into the compartment 14 is attained through the door 16 which is preferably arranged at the rear side of the container 13. Extending upwardly as a continuation of the rear wall of the container 13 is a bracket 17 and the back plate 12 has the upper edge thereof suitably connected to the bracket 17 and has the lower edge thereof suitably connected to the forward edge of the upper side of the container 13 so that it will extend at an angle thereacross which will facilitate the viewing of the articles mounted in the display device.

In the end members 10 and 11 adjacent the apices thereof and extending from said apices in each direction are openings 18. My improved display members are generically indicated by 19 in the drawings and include hinge portions 20 through which pins 21 may be extended. The pin members 21 are of greater length than the display members 19 and are intended to be inserted through aligned openings 18 in the end members 10 and 11 so as to support the display members 19 in substantially book-like arrangement, that is so that the display members 19 may be turned as the pages of a book.

The display members 19 include border strips 22 which extend around the edges of the display members 19 and which support a sheet of transparent material 23. Extending transversely across the display members 19 at substantially the midpoint in the longitudinal extent thereof are reinforcing strips 24. The reinforcing strips 25 of the border strips 22 are disposed along the edge opposite the edge providing the hinge 20 and are arranged so as to have reinforcing strips 26 extending between this strip 25 and the re-

enforcing strip 24. When the display members 19 are arranged so as to display three cards in vertical alignment two of these re-enforcing strips 26 are provided as clearly illustrated in Figs. 3 and 5. When but two cards are intended to be illustrated in vertical alignment but one of these re-enforcing strips 26 is provided as clearly illustrated in Fig. 4. Reenforcing strips 27 substantially 5 similar to the reenforcing strips 26 extend between the reenforcing strips 24 and the re-enforcing strips providing the hinge 20.

Arranged on each side of the main sheet of transparent material 23 are smaller sheets 15 of transparent material 28 which are confined between the border strips 22 and the reenforcing band 24 and the reenforcing strips 26. The upper edges of these sheets of material 28 terminate in spaced relation with 20 the strips to which they are juxtaposed and reenforcing bands 29 are provided along these edges and thus pockets 30 are provided on each side of the main sheet of transparent material 23. Sheets of transparent material 25 31 are provided on one side of the sheet of transparent material 23 and this one side may be called the top side when viewed as the pages of a book. These sheets of transparent material are arranged to provide pockets 32 30 which open toward the hinge 20. Reenforcing strips 33 are secured to the hinge 20 and define a substantially rectangular area of a width substantially equal to the area defined between the hinge 20 and the reenforcing strip 24 and a sheet of transparent material 34 is supported by these border strips 33. The border strip 33 opposite the hinged edge 20 is indicated by 35 and when the sheet of transparent material 34 is arranged to lie 35 above the pockets 31 the strip 35 is substantially parallel to and lies substantially above the reenforcing strip 24. On the side of the transparent sheet 34 disposed toward the pockets 31 is a strip of transparent material 36. Pockets substantially similar to the pockets 30 are arranged on the side of the sheet of transparent material 23 opposite the pockets 31.

The articles to be displayed in the device 50 as stated are greeting cards and the like. Single cards and the envelopes therefor are arranged in the pockets 30. However, cards of the so called folded or book type if arranged in the pockets 30 would either be arranged 55 so that the interior thereof could not be viewed or if arranged so as to be opened the outer side thereof would not be displayed. Therefore, such cards are arranged in the pockets 31 and have the inside portions thereof arranged in the pockets 31 and the upper or leaf portions thereof are extended across the hinge joint 20 and are retained below the transparent strip 36 as is clearly illustrated in Fig. 4 wherein such cards are indicated by 60 65 37. The flat or single page cards are indicated by

38. It is therefore, apparent that in examining the display device the usual turning over of the display members 19 in a manner substantially similar to the turning of the page of a book will bring the single page or flat cards 70 in the pockets 30 into view. The book cards 37, however, will be arranged so that their front or outer faces will be viewed through the sheet of transparent material 34. However, by moving the sheet of transparent material 34 so as to move the edge 35 surrounding the same into the position illustrated in Fig. 5 the interior of such a card 37 will be viewed below the sheet of transparent material 31 and in this manner the entire card may be expeditiously displayed. As the user views the various cards and makes selections on the various display members 19 the pin 21 for the display member 19 having the selected card thereon will be moved outwardly from alignment with the remaining pin members as indicated at 39 in Fig. 3. Therefore, a marker is provided which will permit expeditious return to the various cards selected on the various display members 19 which will greatly expedite the final selection of the desired card. Duplicates of the various cards mounted in the display members will be arranged in the container 13 and after selection has been made of a desired card such a card may 90 be withdrawn from the container 13. It is apparent that since the various cards are displayed below transparent members that they may be expeditiously viewed and at the same time direct handling thereof will be prevented and cards will also be protected against dust accumulation and it is, therefore, apparent that soiling of the cards will 95 be prevented.

While I have illustrated and described the preferred form of construction for carrying my invention into effect, this is capable of variation and modification, without departing from the spirit of the invention. I, therefore, do not wish to be limited to the precise 105 details of construction set forth, but desire to avail myself of such variations and modifications as come within the scope of the appended claims.

Having thus described my invention what 115 I claim as new and desire to protect by Letters Patent is:

1. A display device for greeting cards of the book type comprising a case including upper and lower wall members having slots 120 therein and pins slidably mounted in said slots, a plurality of card supporting frames arranged like the leaves of a book and each mounted on one of said pins and each including parallel sheets of transparent material 125 providing pockets on one face of each frame with said pockets opening toward said pins, a transparent sheet extended across the other face of each frame, and a transparent strip extended from top to bottom across each 130

of said last named sheets whereby when one leaf of said greeting card is inserted under said strip and the other leaf thereof inserted in a corresponding pocket on the adjacent frame the entire four pages of the card will be exposed to view.

2. A display device for greeting cards of the book type comprising a case including upper and lower wall members having slots therein and pins slidably mounted in said slots with portions extended beyond said members, a plurality of card supporting frames arranged like the leaves of a book and each mounted on one of said pins and each including parallel sheets of transparent material providing pockets on one face of each frame with said pockets opening toward said pins, a transparent sheet extended across the other face of each frame, and a transparent strip extended from top to bottom across each of said last named sheets whereby when one leaf of said greeting card is inserted under said strip and the other leaf thereof inserted in a corresponding pocket on the adjacent frame the entire four pages of the card will be exposed to view, and said pins may be pulled out of normal position to mark selected cards.

In testimony whereof I affix my signature.

WALTER C. HOFFMAN.
